UNITED STATES PATENT OFFICE

JULES L. LOZEA, OF NEW YORK, N. Y.

DESIGN FOR A PAIR OF OXFORD EYEGLASSES

Application filed February 19, 1932. Serial No. 42,930. Term of patent 14 years.

To all whom it may concern:

Be it known that I, JULES L. LOZEA, a citizen of the United States, residing at New York, in the county of New York and State of New York, have invented a new, original, and ornamental Design for a Pair of Oxford Eyeglasses, of which the following is a specification, reference being had to the accompanying drawings, forming part thereof.

Figure 1 is a front elevational view of a pair of oxford eyeglasses, showing my new design,

Figure 2 is a top plan view thereof, and
Figure 3 is a perspective view of the same.
I claim:

The ornamental design for a pair of oxford eyeglasses, as shown.

JULES L. LOZEA.
